SELECTIVE TUNING SYSTEM

George S. Wachtman, Harrisburg, Pa.

Original application October 5, 1943, Serial No. 505,048. Divided and this application November 14, 1944, Serial No. 563,385

1 Claim. (Cl. 250—40)

My invention relates broadly to circuit arrangements for high frequency oscillators and more particularly to a circuit for controlling the resonant frequency of tunable circuits over a variable frequency range with a high degree of precision.

This application is a division of my application Serial Number 505,048 for Electron tube apparatus, filed October 5, 1943.

One of the objects of my invention is to provide an improved circuit arrangement for controlling the resonant frequency of electrically tunable circuits with a high degree of precision.

Another object of my invention is to provide a dual condenser controlled variable frequency oscillator circuit including a series connected adjustable means for compensating for the effectiveness of the respective portions of the dual condenser at any point in the frequency range of the oscillator circuit.

Other and further objects of my invention reside in the improved circuit arrangement for electrical tuning systems as set forth in the following specification and shown in the accompanying drawing in which:

Figure 1 diagrammatically shows the circuit of my invention; Fig. 2 shows a curve diagram showing the ideal characteristic curves of the circuit arrangement of my invention; and Fig. 3 illustrates practical conditions which may be encountered unless high precision operation is secured in the frequency control system of my invention.

Referring to the drawing which diagrammatically shows the oscillator system of my invention, reference character 1 designates the broad tuning condenser and reference character 2 shows the fine tuning dual condenser connected with impedance 3 as shown. The dual condenser 2 comprises a pair of fixed stator sections 2a and 2b and a central rotor 2c and constitutes a split-stator or dual section variable condenser having capacities which vary simultaneously in the same direction. Reference characters 5 and 7 designate the trimmer condensers, whereby the control action of the fine tuning dual condenser 2 may be adjusted and reference character 8 designates a condenser whereby the minimum or lowest tunable frequency of the combination may be adjusted.

A variable capacity condenser shown at 46 is connected in series between the rotor 2c of the dual condenser 2 and the impedance device 3. The variable condenser 46 is provided with a pad or trimmer condenser 47 in parallel therewith for

increasing the precision adjustment of the circuit. Condenser 47 is set or adjusted so that condenser 46 has that variation in capacity required for compensating for the lack of linearity in dual condenser 2 as shown in characteristic curve C' in Fig. 3.

Due to the fact that the two sections 2a and 2b of the dual condenser 2 always exert some control over the resonant frequency of the circuit regardless of the setting of the main tuning control 1, the ideal control characteristic for each section of the dual condenser is illustrated by curves A and B and resultant curve C shown in Fig. 2 plotted with respect to total bandspread as ordinates and the tuning range of the main tuning control as abscissor. In practical operation it is realized that such theoretically perfect operation may not be achieved.

Instead curves A' and B' of Fig. 3 are actually obtained for the characteristics of the circuit of Fig. 1, the curve C' being the resultant. Consequently, the means of compensating for the non-linearity of curve C', Fig. 3, as provided in the circuit of Fig. 1 are important where accurate frequency controlled work is to be performed with the circuit. This is accomplished by the variable condenser 46 and the coaxing pad or trimmer condenser 47 in parallel therewith operating in combination with the dual condenser 2. The action of the compensating condensers 46 and 47 is to adjust the minimum and maximum capacity of the parallel combination, thereby effectively controlling the tuning range of the bandspread control.

The circuit arrangement of my invention may be utilized for many purposes. The oscillator circuit may be connected to an oscillation system employed to test lapped quartz blanks for activity and frequency to a close tolerance before they are hand finished and put in holders. The circuit can also be used in receivers where it is desired to have a continuous bandspread of frequency; i. e., one that is constant at any setting of the main tuning control. In conjunction with a local piezo-oscillator (frequency to be determined by type of use) and a receiver, and used in a stable variable frequency generator circuit by "standardizing" at time of use, the circuit can be used to determine the frequency of another signal within a few cycles. This is done by heterodyning the signal emitted by the generator against the unknown signal and detecting the heterodyne beat by audible or electrical or electro-mechanical means and then reading frequency by interpolation from a known standard signal (local

piezo-oscillator) and the calibration on the dial of the fine-tuning control. The circuit can also be used to control the frequency of the emitted radiation of a radio transmitter, allowing the frequency to be varied over a wide range, and yet, by means of the fine-tuning control and pre-standardization against a local piezo-oscillator or other primary or secondary frequency standard, control the frequency within a few cycles of the desired frequency.

The applications of this invention, as can be seen from the foregoing, are almost limitless. The control circuit can be applied to any device wherein the resonant frequency is desired to be variable. It can be applied to capacity-inductance or capacity-resistance or other impedance-tuned generators or oscillators, to tuned circuits, such as radio frequency, intermediate frequency or audio frequency stages in amplifiers, receivers, filters, etc., or to other tuned circuits wherein any combination of capacity, inductance, resistance, or reactance is used.

Features of my invention disclosed but not claimed herein are set forth in the parent application Serial No. 505,048, filed October 5, 1943, for Electron tube apparatus; and my co-pending divisional applications, Serial No. 563,383, filed November 14, 1944, for Tuning system; and Serial No. 563,384, filed November 14, 1944, for Electrical tuning system.

While I have described my invention in one of its preferred embodiments, I desire it to be understood that modifications may be made and

that no limitations upon my invention are intended other than may be imposed by the scope of the appended claim.

What I claim as new and desire to secure by Letters Patent of the United States is as follows:

- 5 An electrical tuning system comprising in combination with an impedance device, a variable tuning condenser having one side thereof connected with a point on said impedance device,
- 10 a dual condenser including a central rotor and a pair of variably related capacity areas constituting a pair of condenser sections whose capacities vary simultaneously in the same direction, one of the condenser sections of said pair being disposed
- 15 in series with said variable tuning condenser and the other of the condenser sections of said pair being effectively connected in parallel with the said variable tuning condenser and effectively in parallel with said impedance device, independ-
- 20 ently adjustable variable capacity means connected in series with each of the condenser sections of said dual condenser, and said central rotor being electrically connected in series with a separate variable condenser and another point
- 25 of said impedance device for adjustably compensating for the effectiveness of the respective condenser sections at any point in the frequency range of the tuning system, and an additional variable condenser connected in parallel with
- 30 said last mentioned separate variable condenser to increase the precision with which the latter may be adjusted.

GEORGE S. WACHTMAN.
